(57) **CLAIM**

The ornamental design for the pet feeder, as shown and described.

DESCRIPTION

FIG. 1 is a front perspective view of a pet feeder, showing my new design.

FIG. 2 is a front side elevation view thereof, the rear elevational view being a mirror image.

FIG. 3 is a top plan view thereof.

FIG. 4 is bottom view thereof; and,

FIG. 5 is a left side elevation view thereof, the right side elevation view being a mirror image.

The broken lines illustrate portions of the pet feeder that form no part of the claimed design.

1 Claim, 5 Drawing Sheets
